Primary Examiner — Keith J Wilson(74) *Attorney, Agent, or Firm* — Design IP(57) **CLAIM**

The ornamental design for an open end friction pile two sided, as shown and described.

DESCRIPTION

FIG. 1 is a front view of an open end friction pile two sided showing my new design;

FIG. 2 right side perspective view thereof;

FIG. 3 front perspective view thereof;

FIG. 4 is a top view thereof; and,

FIG. 5 is a sectional view thereof, taken along line 5-5 of FIG. 1.

The broken lines in the figures show portions of the open end friction pile two sided that form no part of the claimed design. The broken away portion of the open end friction pile two sided shown in FIGS. 1 through 3 represents indeterminate length.
